UNITED STATES PATENT OFFICE.

CHARLES HENRY ANDREW, OF STOCKPORT, COUNTY OF CHESTER, ENGLAND.

GAS-ENGINE.

SPECIFICATION forming part of Letters Patent No. 314,284, dated March 24, 1885.

Application filed March 8, 1884. (No model.) Patented in England September 6, 1883, No. 4,291.

To all whom it may concern:

Be it known that I, CHARLES HENRY ANDREW, a subject of the Queen of Great Britain, residing at Stockport, in the county of Chester, 5 England, have invented a new and useful Improvement in Gas-Engines, (for which I have obtained a patent in Great Britain, No. 4,291, bearing date September 6, 1883,) of which the following is a specification.

10 My invention relates to those gas-engines in which the combustible charge of gas and air is exploded when under considerable pressure; and the object of my improvement is to relieve the slide-valve of the pressure resulting from 15 the compression and explosion of the charge. I attain this object by fitting a check-valve in the passage between the combustion chamber of the working cylinder and the slide-valve in the manner illustrated in the accompanying 20 three sheets of drawings, in which—

Figure 1 is a side vertical section through the line D E, Fig. 2, and Fig. 2 is an end vertical section through the line A B, Fig. 1, of the slide-valve and combustion-chamber of the power-cylinder of a gas-engine. Fig. 3 is a plan view of the valve-cover, and Fig. 4 is a plan view of the valve-cover and of the slide-valve, and Fig. 5 is a plan view of the slide-valve, all the last three views being on a reduced scale.

30 Similar letters refer to similar parts throughout the several views.

In these views *a* is the combustion-chamber of the power-cylinder *a'* of a gas-engine. The explosive charge of gas and air mixed is conducted under pressure from the charging or compressing cylinder (not shown in the drawings) when a separate charging-cylinder is employed, or when only a single cylinder is employed is drawn through the pipe reservoir or 35 passage *b* and passage *b'* to the slide-valve *c*, and is admitted through the passage and space *a'* to the combustion-chamber *a*, and so to the power-cylinder *a'*, in the following manner: The slide-valve *c* is formed with a port, *c'*, and when 40 the piston (not shown in the drawings) in the power-cylinder *a'* is near the end of its out-stroke one end of this port *c'* comes opposite the passage *b'*, and the other end of the port comes opposite the passage *a'*, thus opening a communication between the pipe or passage *b* and the passage *a'*, leading to the combustion-cham-

ber *a*. The charge is drawn, or, if under pressure, rushes from the pipe or passage *b* through the passage *b'*, port *c'*, and passage *a'*, lifts the mushroom check-valve *d*, and passes into the combustion-chamber *a*. The spring *d'* on the valve-spindle is used to assist in closing the mushroom check-valve *d* as soon as the charge has passed into the chamber *a* and cylinder *a'*, and thus the main charge in the combustion-chamber *a* is shut off from a portion of the charge left in the passage and space *a'*. During the instroke of the piston in the power-cylinder *a'*, and while the compression of the charge is taking place, the hole *e* in the slide-valve *c* comes over the passage *f* in the valve-cover *g*, and gas is thus allowed to pass from the supply-pipe *f'* through the passage *f* and the hole *e* along the slot *e'* into the pocket *e*, where it is ignited at the master-light *h* by means of a current of air admitted through the opening *h'* in the valve-cover *g*. The master-light *h* is kept constantly burning in the chimney *h'* in a division of or near the combustion-chamber *a*. When the piston in the power-cylinder *a'* has 75 compressed the main charge into the combustion-chamber *a*, and a moment before the piston begins its reverse or out stroke, the slide-valve *c* will have moved in the right-hand direction and be in the position shown in Figs. 1 80 and 2, and as the valve continues its traverse the explosive mixture in the passage and space *a'* between the under side of the mushroom check-valve *d* and the slide-valve *c* is ignited and exploded by the flame in the pocket *e*. This 85 preliminary explosion raises the mushroom valve *d* and explodes the main charge in the combustion-chamber *a*. The mushroom check-valve *d* is instantly closed by the force of the explosion, and thus relieves the slide-valve *c* 90 of all pressure from and protects it from any injury by the explosion in the combustion-chamber *a*. When the slide-valve *c* again moves in the left-hand direction, the waste gases in the ignition-pocket *e* escape through a small pipe, 95 *f*', in the valve-cover *g* previous to the pocket *e* receiving a fresh supply of gas.

I have described and shown a mushroom check-valve; but any suitable kind of check-valve may be employed.

100 I am aware that it is not broadly new in gas-engines to interpose a check-valve between the

slide-valve and the combustion-chamber; and therefore I do not broadly claim such a construction or combination.

I am further aware that spring-held valves for controlling the admission of gas to the slide-valve and for allowing its escape from the combustion-chamber are old. These I neither show nor claim.

I am also aware that slide-valves having 10 passages for the admission of gas to the cylinder or combustion-chamber, its ignition, and its escape from said cylinder are not new. These, therefore, I do not broadly claim; but 15 What I claim as new, and desire to secure by Letters Patent, is—

In combination with the slide-valve and the explosion-cylinder of a gas-engine, a spring-held mushroom valve, *d*, which closes the passage between them, a preliminary explosion

chamber or space formed between said slide- 20 valve and said mushroom valve, a burning jet, and an ignition pocket and passage whereby said jet ignites the gas in the preliminary explosion-chamber, blowing open the mushroom valve *d* and exploding the charge in the 25 main explosion-cylinder, whereby said valve *d* is immediately closed, substantially as set forth.

The foregoing specification of my improvement in gas-engines signed by me this 20th 20 day of February, 1884.

CHARLES HENRY ANDREW.
